2 SHEETS—SHEET 2.

THE DOTS IN THIS DIAGRAM MAY BE TAKEN AS REPRESENTING APPROXIMATELY THE POSITIONS OF THE RESPECTIVE CRANK-PINS AT THE BEGINNING AND TERMINATION OF THE EXPRESSED FUNCTIONS.

SECONDARY CRANK IS APPROXIMATELY 45° IN ADVANCE OF TERTIARY CRANK.

TERTIARY CRANK IS TWICE THE LENGTH OF SECONDARY CRANK.

UNITED STATES PATENT OFFICE.

SYLVESTER LOGAN, OF FRANKLIN, PENNSYLVANIA, ASSIGNOR, BY DIRECT AND MESNE ASSIGNMENTS, OF ONE-HALF TO LOWE E. SIMPSON AND ONE-HALF TO ORVILLE SIMPSON, BOTH OF CINCINNATI, OHIO.

INTERNAL-COMBUSTION MOTOR.

1,135,943.

Specification of Letters Patent. Patented Apr. 13, 1915.

Application filed August 7, 1911. Serial No. 642,697.

To all whom it may concern:

Be it known that I, SYLVESTER LOGAN, citizen of the United States, residing at Franklin, in the county of Venango and State of Pennsylvania, have invented certain new and useful Improvements in Internal-Combustion Motors, of which the following is a specification.

The object, construction and operation of my improved motor are herein set forth with sufficient clearness to enable those skilled in the art to which it appertains to make and use the same.

In the drawings, I have shown one construction by means of which my inventive idea may be mechanically embodied, but said drawings are considered by me to be illustrative merely as there are several other forms of construction whereby said idea may be rendered practicable.

The object of this invention is, to provide an internal combustion motor of the four-stroke cycle type, wherein valves of the usual type, which require a certain amount of power for their operation, are dispensed with, and pistons of a novel construction and arrangement, which contribute to the power output of the engine, are substituted in the place thereof.

Briefly stated, my invention consists in the novel combination of three pistons, arranged to be each acted upon by the pressure developed in a single combustion chamber, two of said pistons being adapted as controlling means for the inlet and exhaust ports communicating with said chamber, together with suitable mechanical elements, such as connecting rods, crank shafts, etc., for converting said pressure into available power.

The various figures of the drawings are as follows:

Figure 1 is a central vertical section through my improved motor, showing substantially the relative positions which the pistons occupy during a portion of the exhaust stroke of the primary piston. Fig. 2 is the same section, showing substantially the position which the pistons occupy during the intake stroke of the primary piston. Fig. 3 is a diagram showing the position and travel of the several pistons throughout the various functions of a complete cycle,

also the relative positions of said pistons at all times.

The construction shown in the drawings is substantially as follows:—I construct a primary cylinder 1, in which a piston 2 of the usual type operates, and which is connected by means of a connecting rod 3 to a crank shaft 4, which is designed to revolve in the direction indicated by the arrow. This primary piston operates upon the four-stroke cycle. Within a secondary cylinder 5 I place two pistons,—a secondary sleeve-piston 6 and a tertiary piston 7, which are connected by means of connecting-rods 6' and 7' to two cranks upon the crank-shaft 8, and the tertiary or inner piston 7 has a stroke which is preferably about twice the length of the stroke of the secondary piston 6. Pistons 6 and 7 are so proportioned that they present substantially the same amount of area to the explosive pressure. Cranks to which the pistons 6 and 7 are connected are so positioned that the secondary piston is in advance of the tertiary piston substantially 45°. Upon the secondary crank-shaft 8 is secured a gear 9 which meshes with a pinion 10 upon the main crank-shaft. Pinion 10 is one half the diameter of gear 9 so that the secondary crank-shaft 8 revolves at one half the speed of the main crank-shaft 4. Through the wall of the secondary cylinder 85 is formed an exhaust port 11, also an inlet port 12, and through the wall of the secondary piston is also formed an inlet passage 12'.

During the exhaust function of the motor 90 the pistons occupy substantially the positions shown in Fig. 1, in which the exhaust port is uncovered by the upper end of the secondary piston as it moves downward past the same, thus permitting the free escape 95 of the products of combustion. By a reference to Fig. 3 it will be noted that during the exhaust function, the primary piston travels upward, the secondary piston travels both downward and upward through 100 the lower quarter of its stroke, and the tertiary piston travels downward through the lower quarter of its stroke. It may also be seen by a reference to Fig. 3 that during the intake stroke the pistons all occupy substantially the position shown in Fig. 2, at

which time the intake passage 12' in the secondary piston is in communication or registry with the intake port 12 in the cylinder wall, the tertiary piston 7 being positioned so as to uncover the inner end of said port 12', thus affording free ingress for the fuel supply to the combustion chamber.

By again referring to Fig. 3 it will be noted that the movements of the various pistons during the intake function are as follows: The main piston 2 is moving downward, and the secondary piston 6, also the tertiary piston 7 are moving upward. The principal and beneficial point, however, in the action of the pistons, and the one which causes them all to contribute to the power output of the motor and to increase its mechanical efficiency over others, is the fact that all of the pistons act in response to and in harmony with the impulse of explosion,—as will be seen by referring to Fig. 3,—and thus all contribute to the power output and mechanical efficiency of the motor.

While the secondary piston is here referred to as a sleeve-piston, it should be carefully noted that it is not such an element as is commonly termed in this art as a "sleeve," for the reason that the elements commonly termed sleeves in this art, are simply valves, and perform functions as such only, whereas my sleeve-piston not only performs valve functions, but in addition thereto it is adapted to be and is acted upon and actuated by the expansive force developed in the combustion chamber and cooperates with the other pistons in converting said force into available power.

The drawings are intended to be illustrative of the inventive idea above set forth, viz:—that the expansive force developed by the combustion of fuel in a single combustion chamber common to two cylinders of a motor, may be active upon at least three pistons, so arranged that they all act in response to and in harmony with such expansive force in said chamber, and are actuated thereby thus all contributing to the power output of the motor; and as a necessary practical adjunct to this, the idea also includes suitable mechanism, such as cylinders for said pistons, crank shafts, connecting rods and reducing gearing such as are suitable for converting such expansive force into available power.

While I have here specifically set forth that the tertiary piston has a stroke that is approximately twice as long as the stroke of the secondary sleeve-piston, and have shown in Fig. 3 that the crank of the second piston is approximately 45° in advance of the crank of the tertiary piston, I wish to be understood as making these statements with reference to the construction

here shown only, as these particulars might be reversed as to said pistons, and other details of construction might be considerably modified without departing from the scope of my invention.

Any suitable form of ignition plug may be inserted in the tap-hole 13 provided therefor.

I claim—

1. In a motor, the combination of a chamber adapted to contain an expansive fluid, a first cylinder having communication with said chamber, a second cylinder offset from said first cylinder and having communication at one end with said chamber, a piston operative in said first cylinder, two pistons operative in said second cylinder, said two pistons being arranged as controlling means for the inlet port and for the exhaust port which extend through the wall of said second cylinder, all three of said pistons being adapted to be actuated by the expansive force of the fluid within said chamber, and means for converting said actuation into available power.

2. A four-cycle gas engine comprising a valve-casing having one end constantly in communication with the combustion chamber of the engine and provided with a fuel inlet port and provided with an exhaust port nearer said combustion chamber, a first valve member working in said valve casing and adapted to have its end coöperate with the before mentioned exhaust port and provided with an inlet port to coöperate with the first mentioned inlet port, a second valve member having its end adapted to coöperate with the inlet port of the first valve member, and valve moving mechanism actuated by the engine and adapted to move the two valve members differentially and to give the two valve members one impulse for each two impulses of the engine.

3. A four-cycle gas engine comprising a valve casing having one end constantly in communication with the combustion chamber of the engine and provided with a fuel inlet port and provided with an exhaust port nearer said combustion chamber, a first valve member working in said valve casing and adapted to have its end coöperate with the before mentioned exhaust port and provided with an inlet port to coöperate with the first mentioned inlet port, a second valve member having its end adapted to coöperate with the inlet port of the first valve member, and valve moving mechanism actuated by the engine at half the speed of the engine and adapted to move the two valve members differentially so that the movement of the first valve member effects the opening of the inlet port to the valve casing, and the movement of the second valve member closes the inlet to the valve casing.

4. A four-cycle gas engine comprising a

cylindrical valve casing having one end constantly in communication with the combustion chamber of the engine and provided with a fuel inlet port and provided with an 5 exhaust port nearer said combustion chamber, a first cylindrical valve member working in said valve casing and adapted to have its end coöperate with the before mentioned exhaust port and provided with an inlet 10 port to coöperate with the first mentioned inlet port, a cylindrical second valve member having its end adapted to coöperate with the inlet port of the first valve member, and valve moving mechanism actuated 15 by the engine and adapted to move the two valve members differentially and to give the two valve members one impulse for each two impulses of the engine.

5. A four-cycle gas engine comprising a 20 valve casing disposed substantially parallel with and having one end constantly in communication with the combustion chamber of the engine and provided with an inlet port and provided with an exhaust port nearer 25 said combustion chamber, a first valve member working in said valve casing and adapted to have its end coöperate with the before mentioned exhaust port and provided with an inlet port to coöperate with the first mentioned inlet port, a second valve member having its end adapted to coöperate with the inlet port of the first valve member, and valve moving mechanism actuated by the 30 engine and adapted to move the two valve members differentially and to give the two valve 35 members one impulse for each two impulses of the engine.

6. A four cycle gas engine comprising a combustion chamber, a main cylinder communicating with said chamber, a valve casing having one end constantly in communication with said combustion chamber, the axis of said valve casing being offset from the main cylinder, the valve casing being 40 provided with an intake port and an exhaust port nearer to the combustion chamber, two valve members working in said casing and adapted to coöperate with each other and with said ports and without the 45 agency of any additional stationary member, whereby the inlet of fuel to and the exhaust of burnt gases from said combustion chamber are effected, and valve moving mechanism actuated by the engine and 50 adapted to move the two valve members differentially and to give them one impulse for each two impulses of the engine.

7. In a gas engine, the combination of a 55 combustion chamber, a main cylinder and a valve cylinder arranged to one side of the main cylinder, said valve cylinder communicating with said combustion chamber at

one end, the valve cylinder being provided with a supply and an exhaust port entering it directly through one of its walls, a main 65 piston in the main cylinder, a valve sleeve in the valve cylinder directly coöoperating with the walls thereof and with said ports, a valve piston within said valve sleeve and directly coöoperating with the sleeve walls, 70 the valve sleeve being provided with a port through one of its walls directly coöoperating with said valve piston and said inlet and exhaust ports, a crank shaft and connections between the same and said main piston, 75 valve sleeve and valve piston to cause said sleeve and valve piston to move differentially and to regulate the intake and exhaust in relation to the main piston.

8. A four-cycle gas engine comprising a 80 cylindrical valve casing having one end constantly in communication with the combustion chamber of the engine, and provided with a fuel-inlet port, and provided with an exhaust-port nearer to said combustion- 85 chamber, a first cylindrical valve-member working in said casing and provided with a passage adapted to coöperate directly with said ports, a cylindrical second valve-member having its end adapted to coöperate directly with the passage in the first valve member, and valve moving mechanism actuated by the engine and adapted to move the two valve members differentially and to give to said two valve members one impulse 90 for each two impulses of the engine.

9. A four-cycle gas engine comprising a cylindrical valve-casing having one end constantly in communication with the combustion chamber of the engine, and provided with a fuel-inlet port, and provided with an exhaust-port nearer to said combustion- 100 chamber, a first cylindrical valve member working in said casing and provided with a passage adapted to coöperate with said casing-ports at different intervals, a second cylindrical valve-member having its end adapted to coöperate with the passage in the first valve-member, and valve-moving mechanism actuated by the engine, adapted 105 to move said two valve-members differentially and to give to said two valve-members one impulse for each two impulses of the engine, both of said valves being arranged and adapted to coact with the motor-piston 110 in the communication of the explosive force within the cylinder, to the crank shaft of the motor.

In testimony whereof I affix my signature in presence of two witnesses.
